BURIAL VAULT COVER FORMING UNIT

Wilbert W. Haase, Jr., Fond du Lac, Wis., and Richard G. Reichle, Riverside, and John E. Wennerberg, Jr., Forest Park, Ill., assignors to American Wilbert Vault Corporation, Forest Park, Ill., a corporation of Illinois

Filed Dec. 30, 1964, Ser. No. 83,228

Term of patent 14 years

(Cl. D54—8)

FIG. 1 is a side elevational view of a burial vault cover forming unit, embodying our new design;

FIG. 2 is a top plan view thereof;

FIG. 3 is a front elevational view as seen from the left hand side in FIGS. 1 and 2;

FIG. 4 is a rear elevational view as seen from the right hand side in FIGS. 1 and 2; and

FIG. 5 is a bottom plan view thereof.

We claim:

The ornamental design for a burial vault cover forming unit, substantially as shown.
